(57) **CLAIM**

The ornamental design for a classroom chair, as shown and described.

DESCRIPTION

FIG. 1 is a front isometric view of a first embodiment of a classroom chair;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawing views are included for purposes of illustrating environment and form no part of the claimed design. The broken sections shown in the drawing views are meant to disclose indeterminate length.

1 Claim, 4 Drawing Sheets(56)
